By Higdon & Longau, Atty's.

UNITED STATES PATENT OFFICE.

ENOS L. WALKER, OF ST. LOUIS, MISSOURI.

DESIGN FOR A BERRY-BOX BLANK.

SPECIFICATION forming part of Design No. 31,998, dated December 19, 1899.

Application filed October 16, 1899. Serial No. 733,837. Term of patent 14 years.

To all whom it may concern:

Be it known that I, ENOS L. WALKER, of the city of St. Louis, State of Missouri, have invented and produced a new and original 5 Design for a Berry-Box Blank, of which the following is a full, clear, and exact description, reference being had to the accompanying drawings, forming a part hereof.

Figure 1 is a plan view of my design for a berry-box blank. Fig. 2 is an end view of the same.

The blank 9 contains many well-known features, such as the divergent cuts 1, extending from the points 2 to the ends of the blank 9, 15 the creases 7, extending from said points to the side of said blank, and the creases 11, joining longitudinally with the points 2 2.

The essential features of my design consist of the creases 3, extending diagonally inward 20 from the points 2 to the points 4, and the

creases 5, joining transversely the points 4, throwing the ends of the creases 5 diagonally inward from the ends of the creases 11, of the V-shaped excisions 8, lying partly in the flaps 13 and partly in the end flaps 6, the points of said V-shaped excisions being the outer ends of the cuts 1, and of the sloping edges 14 of the flaps 13, beginning approximately at the outer ends of the creases 7 and extending to the ends of said flaps. 25

I claim—

The design for a berry-box blank, substantially as herein shown and described.

In testimony whereof I affix my signature in presence of two witnesses.

ENOS L. WALKER.

Witnesses:

EDWARD E. LONGAN,
JOHN C. HIGDON.
